(57) **CLAIM**

The ornamental design for an X-ray device, as shown and described.

DESCRIPTION

FIG. 1 is a top front perspective view of an X-ray device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another front view thereof, showing the X-ray device in another configuration.

The broken lines illustrating portions of the X-ray device are for environmental purposes only and form no part of the claimed design.
